(57) **CLAIM**

The ornamental design for a spa light with solar power panel, as shown and described.

DESCRIPTION

FIG. 1 is perspective view of a spa down light with solar power panel showing my new design;

FIG. 2 is a front view thereof;

FIG. 3 is a side view thereof;

FIG. 4 is a rear view thereof;

FIG. 5 is a top view thereof; and,

FIG. 6 is a bottom view thereof.

The broken lines are shown on the drawings for illustrative purposes only and form no part of the claimed design.
